UNITED STATES PATENT OFFICE.

CHARLES HEISLER, OF ST. LOUIS, MISSOURI.

INCANDESCENT ELECTRIC LAMP.

SPECIFICATION forming part of Letters Patent No. 327,796, dated October 6, 1885.

Application filed March 24, 1885. Serial No. 159,960. (No model.)

To all whom it may concern:

Be it known that I, CHARLES HEISLER, of the city of St. Louis, in the State of Missouri, have invented a certain Improvement in 5 Automatic Cut-Outs for Electric Lamps, of which the following is a full, clear, and exact description, reference being had to the accompanying drawings, forming part of this specification.

10 My invention has for its object to provide means for switching in automatically a new incandescent lamp or filament when an old one is destroyed, and for completing the line-circuit when all the lamps or filaments of a 15 given series are exhausted, so that the operation of other lamps or filaments in the same system shall not be interrupted. I accomplish this result by means of a high-resistance electro-magnet in a shunt around the lamp or filament, the position of the armature of the said magnet determining whether the circuit shall be complete through one of the lamps or filaments or directly on to line. In another application filed at the same time herewith I 25 show different magnet-connections; but in that application I confine my claims to the specific construction therein disclosed.

In this application I show two single-filament lamps and a cut-out provided with means for 30 switching in the second when the first is destroyed, and for completing the line, as above indicated, when both are incapacitated for service. Instead of two single-filament lamps I might employ a single lamp having two filaments, 35 and with slight changes I could adapt my cut-out to be used with a greater number of lamps, or with lamps having a greater number of filaments. It will be evident, also, that I could make any other number of lamps or filaments 40 besides one the unit—that is to say, I could switch in two or three or any other desired number of lamps or filaments at a time.

In the drawings which accompany and form a part of this specification, and in which the 45 same letters refer to the same parts throughout, Figure 1 is an elevation of my cut-out with two single-filament incandescent lamps attached thereto, the casing of the cut-out being shown in section. Fig. 2 is a similar view 50 taken from the right of Fig. 1. Fig. 3 is a

diagram showing my lamps and cut-outs arranged in series. Figs. 4 and 5 are side elevations of the cut-out apparatus alone, taken respectively from the rear and left of Fig. 1. Fig. 6 is a cross-section through line 6 6 in 55 Fig. 1, looking down. Fig. 7 is a bottom view of the cut-out. Figs. 8 and 9 show the position of the parts when a single lamp is cut out. Figs. 10, 11, and 12 show their position when both lamps are cut out; and Fig. 13 is a diagram of the circuit within the cut-out and lamps. 50

Referring to the drawings by letter, P and P' are two incandescent lamps, and P' and n are their respective filaments. The ends of 65 the filament P' are connected, as usual, to the lamp-terminals, which in this instance assume the form of split posts M and Q. The ends of the filament n are similarly connected to the terminal posts m and N. The lamps are 70 fixed in position by pushing the split posts into the hollow binding-posts l, L², L', and R, two of these binding-posts, L' and L², uniting to form a common connection, L, for the inner ends of the two filaments. It is evident that 75 a current of electricity entering at L may pass through either lamp, according as the return-connections are arranged to complete the circuit of one or the other. Which lamp shall be in circuit at any given time, or whether 80 either shall be, is determined by the condition of my cut-out device, which forms the subject of my present invention, and which I will now proceed to describe in detail.

The cut-out apparatus is supported between 85 two metallic disks, A and B, the former of which may be regarded as a cap, and the latter as the bottom or supporting plate of the device. These parts are maintained in position by the bars or posts C C in the ordinary manner. A cylindrical casing, 3, incloses the apparatus, fitting into the cap A and surrounding the plate B, to which it is secured by a screw. All the parts within and without the casing are insulated from the frame of the apparatus by the disks D and D', of insulating 90 material.

The bracket L is usually formed in one piece with a plate or bar, L², the socketed post R in one piece with a plate or bar, r', and the sock- 95 100

eted post *l* in one piece with a plate or bar, *k*. These plates or bars and their connected parts are secured to the bottom of the cut-out by the insulated screws *L*¹, *r*², and *k*². The 5 bracket *L* and the socketed posts *l* and *R* outside the casing of the cut-out are respectively connected to metallic binding-posts *K* *k*, and to a frame, *S*, which supports the shunt-magnet within the casing, as shown in Figs. 1, 2, 10 4, and 7. By reference to Figs. 1 and 7, for example, it will be seen that connection is made between the bracket *L* and the post *K* by means of the plate or bar *k* and the screw 15 10. The same figures show the posts *l* and *k* connected by the plate or bar *k*² and the screw 11, and Figs. 2, 4, and 7 show the post *R* and the frame *S* connected by the plate or bar *r*² and the screw 12. The screws do not come into contact with the bottom of the plate *B*, owing 20 25 to the fact that they fit into openings in the disks *D* and *D*', which are smaller than the corresponding openings in the plate *B*.

Cap *A* is provided with a screw-socket, *E*, for attaching the device to its support, and it 25 also carries the binding-posts *F* and *G*, to which the line-wires *H* and *I* are respectively connected.

In the normal condition of the apparatus the circuit enters at post *F* and passes by wire *H*' 30 to a conducting-bracket, *J*, on the post *K*, and thence through the socketed post *L*', split post *M*, and filament *P*', and back to the post *R* through the terminal post *N*. From *R* it passes to the lower part of a frame, *S*, which supports 35 35 an electro-magnet, *T*, and thence through the springs *d* and *u* and bars *a* and *p*, which parts will be described hereinafter, to the other end of the frame *S*, and so to the post *G* and to the line by way of the wire *I*'.

40 Between the post *K* and the frame *S*, and having its terminals connected to the said posts, there is a high-resistance shunt, including the electro-magnet *T*. This electro-magnet is supported in the frame *S*, as already 45 stated, and has one fixed pole, *W*, and one movable pole, *X*, which latter forms the armature of the magnet. It is jointed at *Y* and extends up, so that its free end is in proximity to the pole *W*. A spring, *Z*, made of non-magnetic material, keeps the two poles normally apart. The armature has attached to it a non-magnetic bracket, which is provided 50 with catches *e* and *t*, as shown. With the catch *e* normally engage ratchet-teeth *b* and *r* on the bars or rods *a* and *p*, respectively. Springs *d* and *u* tend normally to press the 55 said bars or rods upward, carrying the attached brackets or arms *e* and *v* with them.

A pair of pins, *f* and *w*, project out from the 60 said brackets or arms under the ends of two pairs of spring-arms, *g* *h* and *x* *y*, and when the bars or rods are released, as they will be when the catches are moved out of the way of the ratchet-teeth by the attraction of the armature, these pins make contact each with the spring-arms of a different pair, for a purpose to be presently explained. The bar *p*,

however, is provided with ratchet-teeth *s* and *q*, arranged in such relation that the tooth *s* will engage the catch *t* when the armature is 70 attracted, and the tooth *q* will engage the catch *e* when the armature is restored. A single attraction of the armature liberates the bar *a*. It takes two inward movements to set the bar *p* free. The spring-arms *g* and *y* are connected 75 through the frame *S* and the wire *I*' with the post *G* and one end of the line. The spring-arms *x* and *h* are connected one through the bracket *K*', post *K*, and wire *H*' with the post *F* and the other end of the line, and the other 80 through the bracket *i*, wire *j*, and post *k* with the socketed post *l*, through which the circuit of lamp *P*' passes.

The resistance of the magnet *T* is so great that very little of the current passes through 85 it in the ordinary working of the apparatus. When, however, the filament *P*' breaks, or for any other reason the lamp *P* becomes inoperative, the entire current passes through the magnet and causes it to attract its armature. This being understood, the function and operation of the remaining parts above described will now be explained. When the free end of the armature moves inward, in obedience to the attraction of the magnet, the 90 ratchet-bars *a* and *p*, together with their respective brackets and the pins *f* and *w*, are released. The bar *p*, however, is immediately caught again by the engagement of the ratchet-tooth *s* with the catch *t*. The pin *f* 95 on being released makes connection between the spring-arms *g* and *h* and completes a new circuit, as follows: from post *F* by wire *H*', posts *K* and *L*', split post *N*, through filament *n* to post *m*, and thence by binding-post *l*, post *k*, wire *j*, bracket *i*, spring-arm *h*, pin *f*, 100 spring-arm *g*, frame *S*, wire *I*', and post *G* to line. The moment this new circuit is completed the magnet *T* is short-circuited and its armature is restored, releasing the ratchet-tooth *s*, but again catching the bar *p* by 105 reason of the tooth *q* engaging with the catch *e*. A similar operation takes place on the failure of the second lamp, the entire current being forced through the magnet, as 110 before. This time, however, the bar *p* is entirely released and closes a short circuit, as follows, around both lamps: from post *F* by wire *H*', bracket *J*, binding-post *K*, bracket *K*', spring-arm *x*, pin *w*, spring-arm *y*, spring *z*, wire *I*', binding-post *G*, and thence to line. 115

Besides the above-described automatic means for cutting out the lamps, I provide the following manual means to enable me to switch the apparatus into or out of circuit at any time 120 I may wish. A switch-spring, *z*, is attached to a small shaft, *1*, pivoted in the bracket *J*, and having a knob, *2*, outside of the casing *3*, whereby both the shaft and the spring may be turned. It is evident that by turning the 125 spring *z* into contact with the binding-screw 4, to which the wire *I* is connected, the whole apparatus will be short-circuited and the lamps *P* and *P*' cut out.

I have found that the attractive force of the pole W for the pole-armature X is considerably greater than if the armature is disconnected from the magnet. This construction 5 of magnet gives special value for the present purpose, where the resistance of the spool-wire must be much greater than the resistance through the lamp, and where there is not space for a large spool without making an unsightly 10 appearance. To give sufficient resistance without using too large a spool, I use very fine wire of a material whose conductivity is somewhat low, such as German-silver. This gives 15 a magnet of small power where an ordinary armature is used; but with the pole-armature I am able to get the needed attractive force, either with a constant or with an alternating current.

As incandescent lamps are often used in 20 damp places, I have found it necessary to take measures for rendering my electro-magnet weather-proof, it being well known that moisture is likely to injure the insulation of the spool-wire, thereby causing short circuits, and 25 in time the destruction of the wire. To obviate this I saturate the coil with some water-proof material, such as varnish or oil. For a similar reason I also saturate the cement in the neck of my lamp globes or receivers with 30 water-proof material.

As a means for simultaneously restoring the rods *a* and *p* to their lower position, I have a push-rod, 5, with a foot, 6, which by the depression of the rod is brought in contact with the upper ends of the rods and forces them down until the armature-tooth *c* engages the teeth *b* and *q* of the rods. The part of the foot 35 6 coming in contact with the rods should be of insulating material, so that the electric current shall not pass from the rods into the foot when they are in contact. The rod 5 works in a tubular post, 7, which contains a spiral spring, 8, whose upper end bears against the head 9 of the rod 5 and carries up the foot out 40 of contact with the rods *a* and *p* when the pressure of the finger has been removed from the head 9. The head or knob plays upon the outside of the tubular post 7 as a guide.

As a modification, the rod *p* may be a duplicate of the rod *a*, and the device may be used for a single lamp to short-circuit the electric current and cut out the lamp when it may have become disabled from any cause, the purpose of duplicating the rod *a* being to make 45 the short-circuiting contact almost certain, as on the failure of one rod, *a*, the other would act.

It is of course understood that the members of each pair of spring-arms are normally insulated from each other, the insulating material *U* serving that purpose for one pair and *U'* for the other.

An alternating current may be used with my device, as the alternations are so rapid that 65 the armature will be held constantly in its outer or inner position, according as a part or all of the current is passing through the mag-

net-coil. The current may, of course, if constant, traverse the apparatus in either direction, from F to G or from G to F.

In Fig. 13 the parts are misplaced and drawn to an independent scale, the design being simply to show the circuits clearly.

Having now described my invention, what I claim, and desire to secure by Letters Patent, 75 is—

1. The combination, with two or more incandescent lamps or conducting filaments, one of which is in the main circuit of an electric lighting system, of an electro-magnet in a 80 high-resistance shunt-circuit, the said electro-magnet being provided with means for closing the circuit of a second lamp or filament when the first is destroyed or fails for any other reason, substantially as set forth. 85

2. The combination, with two incandescent lamps or conducting filaments, an electro-magnet in a high-resistance shunt around the first lamp or filament, and means operated by the action of the electro-magnet for switching 90 in the second lamp or filament when the first is destroyed, of means, also operated by the action of the electro-magnet, for closing the circuit around both lamps or filaments, substantially as and for the purpose set forth. 95

3. In an apparatus for switching in a new incandescent or filament on the failure of the one in use, an electro-magnet, a catch or detent on the armature thereof, a series of spring-actuated bars engaging with the said catch, 100 and means actuated by successive operations of the magnet, whereby the said bars will be successively released and close the circuit of new lamps or filaments, substantially as set forth.

4. In an apparatus for switching in a new 105 electric incandescent lamp or filament on the failure of the one in use, an electro-magnet in a high-resistance shunt around the first lamp or filament, a catch or detent on the armature thereof, a series of spring-actuated notched 110 bars engaging with the said catch, and a series of contact arms or springs arranged in pairs, one of each pair forming one terminal of one of the unused lamps or filaments, and means actuated by successive operations of the magnet, whereby the notched bars are released 115 and make contact successively between the terminals of all the pairs, substantially as and for the purpose set forth.

5. In an apparatus for switching in a new 120 incandescent lamp or filament on the failure of the one in use, an electro-magnet, *T*, in a shunt-circuit around the first lamp or filament, an armature, *X*, catches *c* and *t*, bars or rods *a* and *p*, ratchet-teeth *b*, *q*, *r*, and *s*, and springs 125 *g* *h* and *x* *y*, arranged in pairs, one spring of each pair being connected with one pole of the generator, and each of the other springs being connected with the opposite pole through a different lamp or filament, substantially as and 130 for the purpose set forth.

6. The combination, with two or more electric lamps or filaments, one of which is in the main circuit of an electric lighting system, of

an electro-magnet in a high-resistance shunt-circuit, the said electro-magnet being provided with means for closing the circuit of a succeeding lamp or filament when the one in use is destroyed, the coils of the said electro-magnet being also saturated with moisture-proof material, substantially as and for the purpose set forth.

7. The combination, in a single device, of
10 a socket or support provided with means for
attaching two or more incandescent lamps and

15 electro-magnetic switch and cut-out devices, the electro-magnet being wound with German-silver wire and having one of its poles hinged or jointed and extending out into the range of the other pole, substantially as and for the purpose set forth.

CHARLES HEISLER.
